(57) **CLAIM**

The ornamental design for filter frame holding flexible, irregular media, as shown and described.

DESCRIPTION

FIG. 1 is a perspective view, showing our new design of a filter frame holding flexible, irregular media;

FIG. 2 is a top plan view of the filter frame holding flexible, irregular media depicted in FIG. 1;

FIG. 3 is a side elevational view of the filter frame holding flexible, irregular media depicted in FIG. 1, all other side elevational views having a similar appearance thereto; the flexible, irregular media providing some variation in appearance;

FIG. 4 is a bottom plan view of the filter frame holding flexible, irregular media depicted in FIG. 1;

FIG. 5 is a perspective view of a second embodiment of a filter frame holding flexible, irregular media, the filter media being lined to indicate that it has a blue color;

FIG. 6 is a top plan view of the filter frame holding flexible, irregular media depicted in FIG. 5;

FIG. 7 is a side elevational view of the filter frame holding flexible, irregular media depicted in FIG. 5, all other side elevational views having a similar appearance thereto; the flexible, irregular media providing some variation in appearance; and,

FIG. 8 is a bottom plan view of the filter frame holding flexible, irregular media depicted in FIG. 5.
